CLAIM

The ornamental design for an icon for a portion of a display screen, as shown and described.

DESCRIPTION

The FIGURE is a front view of an icon for a portion of a display screen showing our new design.

The broken line showing of various regions in the FIGURE and the unshaded areas there within form no part of the claimed design. The broken line showing of the portion of a display screen is for illustrative purposes only and forms no part of the claimed design.

The broken line that connects the image of the bottom monitor to the vertical line is claimed subject matter.
